UNITED STATES PATENT OFFICE.

JOHN CAYGILL, OF WHEELING, WEST VIRGINIA.

DRYING-FURNACE.

No. 858,260.

Specification of Letters Patent.

Patented June 25, 1907.

Application filed December 1, 1906. Serial No. 345,934.

To all whom it may concern:

Be it known that I, JOHN CAYGILL, a citizen of the United States of America, residing at Wheeling, in the county of Ohio and State 5 of West Virginia, have invented new and useful Improvements in Drying-Furnaces, of which the following is a specification.

This invention relates to a drying furnace especially designed for drying out molds and 10 the like, the object of the invention being to provide an inexpensive and economically operating type of furnace adapted for the effective generation of a heated current of air designed to be conducted to the mold or 15 molds to dry the interior thereof.

A further object of the invention is to provide a furnace having heating elements which may be conveniently removed when warped or otherwise injured, wherein provision is 20 made for the ready removal of interior parts of the furnace for repairs, and wherein a heated current of air is generated which is combined with the products of combustion from the fire box of the furnace to form the drying current 25 and acts on its passage as a force draft to promote combustion in the fire box.

In the accompanying drawings,—Figure 1 is a front elevation of a drying furnace embodying my invention. Fig. 2 is a vertical 30 cross section of the same. Fig. 3 is a top plan view of the upper head. Fig. 4 is a perspective view of one of the heating cells.

Referring to the drawings, 1 designates the base of the furnace which forms the ash pit 2 35 and is provided with a clean-out door 3 and a horizontal supporting flange 4, on which rests the furnace body 5, which latter is provided at its lower end with a flange 6 resting on said flange 4 and fastened thereto by bolts or 40 rivets 7. The body 5 forms the fire box or chamber 8 and supports a grate 9 which rests upon an inward extension of the flange 6 and is provided with a brace bar 10 bearing against the inner edges of the flanges 4 and 6. 45 The body 5 is provided with a fire brick lining 11 and an outlet flue 12 having a suitable fire-proof lining 12' and is closed at its upper end by a head 13 resting upon a supporting flange 14 at the upper end of the body and 50 detachably secured thereto by bolts or rivets 15.

The head 13 is provided on its under side with a fire-proof lining 16, preferably composed of some suitable plastic material fixed 55 to the head by ribs or projections 17 formed upon the head and embedded in said material.

The head is further provided in its upper side with a series of pockets 18, each communicating with a passage or opening 19 leading downward through the head and lining 16 60 and normally communicating with the fire box 8. Fitting in these openings and projecting downwardly into the upper portion of the fire box are heating cells or chambers 20, conforming in size and diameter to the openings 19 and provided at their upper ends with flanges 21 seated in the pockets 18 and resting upon the bottom walls thereof, whereby said cells are detachably fitted in the pockets and openings and supported by 70 the head. Preferably, a central cell and an annular group of cells surrounding the same are employed, as shown in Fig. 3, this arrangement permitting of the use of a large 75 number of cells in the space allowed and their disposition so as to be both effectively heated by the flames from the bed of fuel, but any other desired arrangement of the cells may be adopted.

The head is provided at its upper end with 80 a flange 22 on which rests a hollow cover plate or cap 23 having a flange 24 to rest upon said flange 23 and detachably secured thereto by bolts or rivets 25. The cap or cover forms a superposed hot air chamber 26 85 communicating with the cells, and is provided with an outlet 27 arranged above the opposite flue 25 of the fire box. Suitably supported by the cap is an air supply pipe 28, through which air, preferably under compression, is supplied to the cells 20, the air being conducted from said pipe to the cells through conducting pipes 29. These pipes connect at their upper ends with the pipe 28 and lead downward through the cap and hot 90 air chamber into the cells. The pipes are of less diameter than the cells and terminate a suitable distance above the bottom of the latter, so that the air entering the cells therethrough will be heated and thence flow upwardly out through the cells into the chamber 26. The cells are constructed of some suitable durable material adapted to be quickly heated by the flames in the fire box and to heat the air in turn to a high degree. 95 The furnace is provided with suitable fire and draft doors 30 and 31.

A discharge pipe or outlet connection 32 is arranged upon the exterior of the furnace and is coupled in any suitable manner to the 100 outlets 12 and 27, and is suitably constructed at its lower end for connection with the mold 110.

or with a conductor leading to one or a series of molds.

It will be understood that the air entering the cells through the pipes 29 will be heated by the heat of the flame within the fire box and will thence pass upward into the chamber 26 and from the same into the discharge pipe 32, while the products of combustion from the furnace will discharge through the outlet 12 into the discharge pipe. The heated air on its downward passage through the pipe 32 will operate as a force-draft to induce and promote combustion of the fuel resting on the grate in the chamber 8, and will be met by and commingle with the products of combustion exhausting through the outlet 12, whereby the air will be heated to a higher degree of intensity. The resultant current of the drying fluid will thence flow through the lower end of the pipe 32 to the mold or molds and, owing to its high degree of temperature, will effect a rapid and efficient drying thereof.

Having thus described the invention, what is claimed as new, is:—

1. A drying furnace having a fire box provided with an outlet flue, a heating chamber arranged above the fire box, and having an outlet, heating vessels extending into the fire box and in open communication with the heating chamber, air conductors leading to said vessels, and a discharge pipe connecting with said outlets.

2. A drying furnace having a fire box with an outlet leading therefrom, an air heater arranged above the fire box and provided with an outlet, means for conducting air to the heater, and a discharge pipe connected at its upper end with the air heater and below the same with the fire box outlet.

3. A drying furnace having a fire box pro-

vided with an outlet, an air chamber above the same and also having an outlet, a series of heating cells closing communication between said fire box and chamber and projecting into the box and communicating with the chamber, and an outlet flue connected with said outlet.

4. A furnace of the character described having a fire box, a head supported thereon and provided with openings, a cap carried by the head and forming an air chamber, the fire box and air chamber being provided with outlets, heating cells supported by the head and projecting into the fire box, said cells being in communication at their upper ends with the air chamber, a source of air supply, conducting pipes leading therefrom to the air cells, and a downwardly extending discharge pipe communicating at its upper end with the outlet from the air chamber and below the same with the outlet from the fire box.

5. A drying furnace having a fire box provided with an outlet flue, a heating chamber arranged above the fire box and separated therefrom by a partition, said chamber being provided with an outlet and the partition with openings, heating vessels fitted in said openings and projecting into the fire box, said vessels being closed at their lower ends and open at their upper ends, means for supplying air to said vessels, and a discharge pipe communicating at its upper end with the outlet of the heating chamber and below the same with the flue inlet.

In testimony whereof, I affix my signature in presence of two witnesses.

JOHN CAYGILL.
